UNITED STATES PATENT OFFICE.

MARCUS M. BEEMAN, OF MEADVILLE, PENNSYLVANIA, ASSIGNOR TO THE SPIRELLA COMPANY, OF MEADVILLE, PENNSYLVANIA, A CORPORATION OF PENNSYLVANIA.

DEVICE FOR STRAIGHTENING METAL STRIPS.

1,034,059.

Specification of Letters Patent. Patented July 30, 1912.

Application filed November 30, 1908. Serial No. 465,187.

To all whom it may concern:

Be it known that I, MARCUS M. BEEMAN, a citizen of the United States, and resident of Meadville, in the county of Crawford, in 5 the State of Pennsylvania, have invented new and useful Improvements in Devices for Straightening Metal Strips, of which the following, taken in connection with the accompanying drawings, is a full, clear, and 10 exact description.

This invention pertains to tools for use in the manufacture of stays or stiffeners for corsets and analogous wearing-apparel, and has special reference to devices for straightening that class of stays composed of wire 15 formed into a succession of loops to produce a flexible flat fabric or strip of uniform width which is afterward cut into various lengths to serve as stays. It has been found 20 that the wire strip thus produced tends to assume a twisted and edgewise curved or coiled condition and must be straightened before it is capable of being used for the purpose stated. I contemplate taking the 25 twist out of the strip by the employment of a specially constructed tool forming the subject-matter of a separate application.

The present invention relates to a device 30 designed to operate on the wire strip after it has been untwisted and whereby the edgewise or transverse curvature of the strip is removed, and the strip straightened and rendered efficient for the required purpose.

The invention comprises the novel combination 35 and arrangement of parts hereinafter described and claimed.

In the accompanying drawing Figure 1 is 40 a plan view of the tool embodying the invention and showing a wire strip of well known form being operated on for the purpose stated; Fig. 2 is a side view of the same; and Fig. 3 is a transverse section on the line X—X on Fig. 1.

The tool comprises a metal bed-plate 1 designed 45 to be secured flatwise by means of screws 2, 2 to a suitable support A indicated by dotted lines in Fig. 2. This plate constitutes a supporting-bed over which the wire strip B is drawn flatwise in the operation 50 of straightening the same. The straightening is effected by means of gages 55 projecting from the top face of the bed-plate and arranged to bear on opposite edges of the strip in its transit over the bed plate.

In practice it has been found that the best

results are obtained by employing three gages which consist preferably of rollers 3, 3, 3^x, journaled respectively on parallel stub-shafts 4, 4, 4^x which are shown as tap-bolts provided with slotted heads, between which 60 heads and plate the rollers are confined. The respective rollers are formed with collars 5, 5, 5^x overhanging the upper face of the strip B and serving as guards to retain the strip in contact with the rollers and 65 supporting bed. The journals 4, 4 of the rollers 3, 3 are screwed into the plate 1, as indicated at 6, 6, Fig. 3. The roller 3^x is located intermediate the rollers 3, 3 and has its journal screwed at 6^x into a movable 70 block 7 whereby the roller 3 can be adjusted in relation to the rollers 3, 3 to accommodate strips of different widths and to cause the rollers to exert greater or less pressure on the edges of the strip according to the 75 degree of curvature in said strip. To effect this adjustment of the roller 3^x the block 7 is mounted to slide in a guide extending midway between the rollers 3, 3. This guide consists preferably of a slot 8 provided in 80 the plate and arranged at right angles to the line of travel of the strip. The block 7 is moved and sustained by a screw 9 parallel with the shaft and working in a threaded bore 10 in the block which acts as a nut 85 so that it is made to slide in said slot when the screw is turned. The screw passes through unthreaded holes in lugs 11, 12 formed on the lower face of the plate 1 at 90 opposite sides thereof, and is held against 90 endwise movement by providing its opposite ends with a head 13 and nut 14 bearing against the respective lugs 11, 12. The nut 14 may be locked to the screw by means of a transverse pin 15 or any other suitable 95 means which permits its removal, and it is preferably formed with a knurled portion to facilitate turning the screw.

It is evident that by drawing the strip through the described tool with proper adjustment of the roller or gage 3^x the co-operating rollers exert opposed forces on the two edges of the strip whereby the strip is entirely relieved of edgewise curvature.

What I claim is:

1. A tool for straightening metal strips comprising a bed-plate provided with a transverse guide, a block movable in said guide, an endwise immovable screw extending across the bed-plate on its lower surface 110

- and engaging said block to adjust the same in said guide, two rollers journaled on vertical axes on the bed-plate on opposite sides of the guide, and a third roller journaled 5 on a vertical axis on said block, said rollers being provided on their upper ends with collars overhanging the strip and being independently and freely rotatable and operated by the strip drawn in contact therewith.
- 10 2. A tool for straightening metal strips comprising a slotted bed-plate over which the strip is to be drawn, a block longitudinally adjustable in the slot, two rollers journaled at opposite sides of the slot and adapted 15 to bear on one edge of the strip in transit, a third roller journaled upon the block and adapted to bear on the opposite edge of the strip, the three rollers being independently rotatable and operated by the strip drawn 20 in contact therewith, and collars on the upper ends of said rollers overhanging the strip.
3. A tool for straightening metal strips comprising a bed-plate over which the strip 25 is designed to be drawn and provided with a transverse slot, the lower face of the plate being provided with a pair of lugs at the opposite ends of the slot, a block longitudinally adjustable in the slot and provided 30 with a threaded bore parallel with the slot, a screw working in the said bore and passing through the aforesaid lugs and provided on one end with a head bearing against the outer side of one lug, a nut locked to the 35 opposite end of the screw and bearing on the outer side of the other lug and operative for actuating the screw to adjust the aforesaid block, a pair of rollers supported on the bed-plate at opposite sides of the slot and adapted to bear on one edge of the strip in transit, and a third roller mounted on the block and adapted to bear on the opposite edge of the strip, the rollers being independently rotatable and operated by the strip drawn in contact therewith. 40
4. A tool for straightening metal strips comprising a transversely slotted bed-plate, a block longitudinally adjustable in the slot and provided with a threaded bore extending parallel with the slot, two rollers journaled at opposite sides of the slot, a third roller journaled on said block, said rollers being independently rotatable and operated by the strip drawn in contact therewith, each of said rollers being provided with a 45 collar arranged to overhang the upper surface of the strip to retain the latter in contact with the rollers and with the bed-plate, and a screw supported at its ends on the lower face of the bed-plate at opposite sides 50 of the latter and provided with means for preventing endwise movement of the same and with means for turning the same, said screw working in the aforesaid block for adjusting the latter as set forth. 55

MARCUS M. BEEMAN.
